G. A. GABRIEL,
ELECTROLYTIC CELL.
APPLICATION FILED NOV. 23, 1906.

2 SHEETS—SHEET 2.

UNITED STATES PATENT OFFICE.

GEORGE A. GABRIEL, OF NEW YORK, N. Y., ASSIGNOR TO BLEACH & CAUSTIC PROCESS COMPANY, OF NEW YORK, N. Y., A CORPORATION OF NEW YORK.

ELECTROLYTIC CELL.

No. 884,653.

Specification of Letters Patent. Patented April 14, 1908.

Application filed November 28, 1906. Serial No. 344,674.

To all whom it may concern:

Be it known that I, GEORGE A. GABRIEL, a citizen of the United States, and a resident of the city of New York, borough of Brooklyn, county of Kings, State of New York, have invented certain new and useful Improvements in Electrolytic Cells, of which the following is a full, clear, and complete disclosure.

My invention particularly relates to that class of electrolytic cells used in the separation and production, on a commercial scale, of certain elements or constituents of liquids contained in an electrolytic solution.

The object of my invention is to improve the general construction and arrangement of such electrolytic cells and is also to improve the electrolytic cells heretofore patented by me in reissued patent granted July 16, 1907, No. 12,672, whereby the convenience, economy and efficiency of such electrolytic cells are increased.

As in my prior patent above referred to, the present improvements are shown in connection with an electrolytic cell known as "Hargreaves" or vertical type, and said improvements, in this instance, particularly relate to means for increasing the hydrostatic pressure upon the porous diaphragm thereof, and also relate to a more convenient, efficient and economical arrangement of the sides of the cell, cathode, insulating material and diaphragm.

The present improvements also comprise other features of construction and arrangement hereinafter to be more fully described and claimed in the accompanying claims.

For a full, clear and exact description of this embodiment of my invention and the said improvements, reference may be had to the following specification and accompanying drawings forming a part thereof, in which,—

Figure 1 is a perspective view of my improved electrolytic cell complete in all its parts and arranged for use; Fig. 2 is a horizontal transverse sectional view thereof, taken horizontally through the central portion of the main body of the cell; Fig. 3 is a central vertical sectional view thereof; Fig. 4 is a perspective view of a part of the anode removed from the cell; Fig. 5 is a vertical sectional view, taken through one end of the extension, above the cell proper, for producing the hydrostatic pressure and Figs. 6 to 9

inclusive are sectional detail views of other forms or modifications of the cathode.

Referring to the drawings, the numeral 1 indicates a U-shaped frame, preferably made of concrete or other stone-like or cementitious and insulating material, and is of a width slightly greater than the combined outside width of the anode. The numeral 2 represents the two sides of the cell. These are made in the form of rectangular plates or frames 3, having the central portions thereof offset, as indicated at 4, to form the cathode chambers.

It should be noted that the rectangular frames 3 and offset portions 4 are entirely complete and closed at the top, the only opening to the outside being through the discharge pipe 50 at the bottom of the offset portions 4. This allows all the hydrogen or other gas generated by the cathode to be confined and drawn off with the liquid produced at the cathode through the pipe 50, after which said gas may be used in any commercial or preferred way, such as for lighting purposes. This construction is particularly advantageous in a cell in which no liquid, such as oil, is used for the purpose of producing the circulation. These frames or plates 2 are attached to the U-shaped frame by means of transverse bolts 5 which pass through suitable holes in said U-shaped frame and through the ends and bottoms of the plates 2.

The cathode of my improved cell may be made as follows: The numeral 6 indicates a foraminous screen of stamped steel metal or wire gauze which is of substantially the same size and shape as the outer edge of the rectangular portion 3 of the outer plate or side 2 of the cell. Upon the inner side of the screen 6 is placed a porous diaphragm 7 which may conform in shape and size to that of the screen 6.

I have found it advantageous to stop off the margins of the perforated portion of the cathode. This I may accomplish by any suitable means. However, I prefer to employ a medium for this purpose, which is an electrical insulator, and at the same time is impervious to the passage of electrolytes. This medium I prefer to apply so that it will be in direct contact with the diaphragm, or so placed in relation to it as to prevent the passage of electrolyte through it to the cathode. In this instance I have accomplished this purpose in the following manner:

Between the marginal edges of the screen 6 and the diaphragm 7 I prefer to place the insulating material 8 so as to form a rectangular opening through which the electrolytic fluid may pass from the diaphragm to the cathode. The insulating material may be one integral piece or formed by rectangular strips. The opening formed by the inner edges of the insulating material 8 should be somewhat smaller than the active perforated portion of the cathode screen; in other words, the perforations should extend beyond outwardly or back of the inner edges of the insulation for the purpose of draining all cathode products into the cathode chamber. But the cathode or active surface thereof need not be larger than the marginal perimeter of the diaphragm against which it impinges. The opening should approximate in size the adjacent surface of the anode which will be described hereafter. These parts, including the diaphragm 7, the insulating material 8, and the foraminous cathode screen 6, are clamped between the marginal portions 3 of the side 2 of the cell and the surfaces of the U-shaped frame 1 and are thereby held in operative position.

The lower side or margin of the insulating material 8 that is clamped between the bottom of the U-shaped portion 1 of the cell and the lower margin 3 of the outer plate 2, forms a dam which prevents the liquid that is drained to the bottom of the cathode chamber from again coming in contact with the diaphragm. Even when the other parts of the insulating material are not used, this lower strip in the present construction should, preferably, be used. The upper marginal portion 3 of the side 2 of the cell impinges, or is forced, toward the lower edge of the upward extension 25, hereinafter to be more fully described. A yielding packing or cement, such as india rubber, is preferably inserted between this upper marginal portion 3 and the lower edge of the extension 25, as well as the other marginal portions of the cell in order to form liquid-tight joints.

The cathode 6 is provided with means for leading away from its outer side the liquid which percolates through the diaphragm, and these may be the same as those described in my former patent above referred to. These means, which I have preferred to call "cathode drainers," may be made in several different forms, examples of which are illustrated in Figs. 6 to 8 inclusive of the drawings. One modification of these cathode drainers which is shown in Figs. 6 and 9 comprises a series of downwardly inclined wires 9, the upper ends of which are twisted around or otherwise attached to the strands or wires forming the cathode screen 6. These wires 9 are inclined downwardly at an angle and are all substantially of the same length. They are preferably made of spring

metal, so as to have considerable resiliency. These wires 9 form means for diverting the liquid which percolates through the diaphragm, away from the diaphragm and from the cathode itself, so that said liquid drops from the ends of the wires or otherwise reaches the bottom of the cathode chamber. I preferably provide a plate 10, which I term a "drain-plate." This drain-plate is preferably of the same material as the cathode 6 and the conduits or wires 9. The drain-plate 10 is forced into contact with the ends of the wires 9 by means of screws 11, the outer portions of which are provided with thumbheads 12. The outer ends of the screws 11 bear against the side-wall or plate 2 of the cell, and the inner screw-threaded ends thereof pass through set-nuts 13 and into screw-threaded bosses 14, carried by the drain-plate 10. These screws 11 are for the purpose of pressing the drain-plate 10 against the ends of the wires or cathode drainers 9 so that the drainers will conduct the caustic soda away from the cathode and out of the field of decomposition by the electric current. As shown in Fig. 6, the drain-plate 10 may be provided with a series of transverse holes 15 which allow the liquid to flow over both sides of the plate.

In Fig. 7 I have shown another construction in which the cathode screen is formed by a metallic plate 16, the projections or drainers 17 being punched or otherwise cut from the body of the plate.

In Fig. 8 I have shown a modification in which the drainers 18 are attached to the drain-plate 19 instead of to the screen or cathode 6. In this case the drainers may be attached in any suitable way, such as by the use of rivets 20.

In Fig. 9 I have shown a modification of the manner of arranging the porous diaphragm. This modification is similar to that shown in Fig. 6, with the exception, however, that a second diaphragm 21 is provided, which is similar in size and outline to the diaphragm 7, but is made upon a base or ground of fabric, composed of wire gauze, instead of fibrous material. This construction gives an additional strength to the cell, and provides an additional thickness to the diaphragm, when it is desired to have the percolation of electrolyte less, or when the hydrostatic pressure of the electrolyte is greater.

In this form of my invention, the anode 120 consists of a plurality of blocks or plates 22, or any suitable material used in such cells, but, as described in my prior patent, these plates are preferably made of so-called "Acheson" graphite.

In the form as shown in Figs. 2, 3 and 4, I have indicated an anode for introducing the current into the cell, comprising the vertical members 22, 23 and 23', the portions 22 providing extended outer surfaces which con-

stitute the active anode faces. This face is large in extent, but need be only as thick as is required for the purpose of good electric conductivity and economy. I have shown 5 these parts 22 of the thickness indicated, so that they may readily reach and contact with the vertical parts 23 and 23' without causing the latter to interfere with other portions of the cell, such as the inner surfaces of 10 the upward extension 25. It will thus be seen that as shown, the inner plates 22 form projection for this purpose and, therefore, may be made to correspond more nearly to the width of the conductors 23 and 23'. The 15 plates above referred to are preferably attached together and to the conductors 23 and 23', by screws or similar devices made of a material similar to the parts themselves, preferably slate or graphite. Holes 44 allow 20 the electrolyte to circulate through and about the lower portions of the anode.

The combined width of the plates 22, the conductors 23 and 23', and the space between the latter, is less than the width of the 25 U-shaped frame of the cell, but greater than the internal width of the extension 25, so that the outer surfaces of the anode are brought close to the corresponding surfaces of the porous diaphragm and allows space 30 for the outward adjustment of the anode toward the cathode to make up for alterations in the area of the surfaces of said parts. A special feature of this form of my invention resides in the means for increasing the hydrostatic pressure upon the diaphragm, thereby increasing the capacity of the cell. This means consists of a rectangular frame or box 35 25, forming an upward extension of the cell, composed of slate or similar stonelike material, which rests upon the vertical ends of the U-shaped frame 1. The sides of this extension may consist of any suitable material, provided the inner faces or surfaces are inactive chemically and electrically as concerns 40 the electrolyte, especially when the latter is impregnated with a nascent anion. This construction is particularly advantageous because the employment of the protecting walls 26, and particularly as the lower edges 45 of the same, act as an effectual means of preventing all action between the anode conductor 23 and portions of the cathode member which otherwise would become exposed thereto. It is preferable that the walls 26 50 cover as much area as possible, even down to the lower limit of the inactive upper margin of the cathode. The sides may consist of slabs 26 which are held in contact with the ends 27 of the box by means of suitable bolts 55 or similar devices. The ends 27 of the box may also be formed integral with the ends of the U-shaped frame 1. The cover 29 of the cell is placed upon the top of this extension 25 and is provided with openings for 60 the passage of the upper end of the con-

ductors 23 and 23' and for the entrance of the pipe 30 which provides for the supply of the brine or other electrolyte, as well as allowing the drawing off of any gas generated that does not pass off through the pipe 38, 70 hereafter referred to. Only I provide suitable braces or struts 39 which extend between the sides 26 of the extension 25 and counteract any tendency of the said sides to be forced inward by extraneous pressure of the edges 3 75 of the plates 2, or for other reasons as when the gas is drawn from the cell under a partial vacuum. It should also be noted that the lower inner edges of the sides 26 of the extension 25 are beveled or rounded so as to obviate any tendency of the corners to form an obstruction to the free circulation of the electrolyte above the anode. The positive connector for supplying the electric current, is attached to the conductors 23 and 23', by 80 connecting caps, as indicated at 31. The negative conductor of the cell may be attached to one of the bolts 5 or to any other suitable part of the cell, as indicated at 32. The cell may be provided with an extension 90 circulating tube or pipe 33, which may have three branches 34, 35 and 36, entering the cell, respectively, above the normal level of the electrolyte, slightly below the normal level of the electrolyte, and near the bottom 95 of the anode chamber. The circulating tube 33 is provided with a small internal tube 37 through which the liquid within the cell may be withdrawn and which is adjustable to determine the level of said liquid. The upper 100 end of the circulating tube 33 may be provided with an extension 38 for venting the same and through which the chlorine or other gas generated by the cell may be withdrawn.

From the above description, the following 105 advantages of the construction set forth will be apparent:

First. By adding the extension to the upper portion of the cell, by which the hydrostatic pressure of the electrolyte may be increased, the passage of the said electrolyte through the diaphragm is made considerably more rapid and the capacity of the cell thereby increased. This is especially apparent if a partial vacuum is used to withdraw the gas from the anode chamber of the cell, inasmuch as this additional hydrostatic pressure counterbalances the effect of the partial vacuum. The use of non-conducting or insulating material for this extension reduces the cost of manufacture and eliminates the use of an interior insulating or inert coating for rendering the face thereof inactive as is the case where the metallic side of the cell is made to extend for the full height 115 of the extension.

Second. By placing the insulating material between the surface of the cathode and that of the porous diaphragm, all of the liquid which passes through the diaphragm 120

immediately comes in contact with the cathode and is completely acted upon by the cathode. This prevents any of the liquid from coming in contact with the cathode and then percolating back through the diaphragm into the cell, which might injure the purity of the electrolyte and produce undesirable chemical reactions, thereby causing a lower efficiency of the cell. Furthermore, this arrangement of the insulating material also makes the active surface of the cathode adjustable in area, so that it may have a predetermined relation or correspondence with that of the adjacent anode. The overlapping of the insulating shield over the perforated portion of the cathode screen, beside confining any cathode products to the cathode chamber, also performs the important function of preventing such cathode products from percolating back into the anode chamber, for reasons well known to the art, and as above set forth.

Third. The arrangement of the anode, as described, permits the same to be easily and quickly made from the commercial graphite as now placed upon the market, and also provides a maximum amount of surface with a minimum amount of weight of material. Such an arrangement also provides for an easy and efficient circulation of the electrolyte within the cell. This circulation is aided, and evenly distributed, by small holes which pass transversely through the plates of the anode adjacent their lower edges.

35 What I claim and desire to protect by Letters Patent, is:

1. In an electrolytic cell, metallic plates forming the sides of said cell, said plates having offset or outwardly extending portions 40 forming closed cathode chambers, the cathodes being situated over the recesses formed by said offset portions.

2. In an electrolytic cell, metallic plates forming the sides of said cell, said plates comprising rectangular marginal portions 45 and offset central portions forming closed cathode chambers, the cathode and diaphragm of the cell being held by said rectangular portions over the recesses formed by 50 said offset portions.

3. In an electrolytic cell, a U-shaped body forming the ends and bottom of the anode chamber, metallic plates forming the sides of said cell, said plates having offset or outwardly extending central portions forming 55 the cathode chambers, and walls presenting inner faces of non-conducting material forming an upward extension of the sides of said anode chamber above said plates for increasing the hydrostatic pressure of the anolyte.

4. In an electrolytic cell, a U-shaped body forming the ends and bottom of the anode chamber, metallic plates forming the sides of said cell, said plates having offset or outwardly extending central portions forming 60

the cathode chambers, walls presenting inner faces of non-conducting material forming an upward extension of the sides of said anode chamber above said plates for increasing the hydrostatic pressure of the anolyte, and ties or braces between the sides of said upward extension.

5. In an electrolytic cell, a U-shaped body forming the ends and bottom of the anode chamber, metallic plates forming the sides of such cell and the cathode chamber, slabs of a material inert to the electrolyte and forming an upward extension of the sides of the anode chamber above said plates, for increasing the hydrostatic pressure of the electrolyte. 80

6. In an electrolytic cell, a U-shaped body forming the ends and bottom of the anode chamber, metallic plates forming the sides of such cell and the cathode chamber, slabs of inert material forming an upward extension 85 of the anode chamber for increasing the hydrostatic pressure of the anolyte, and a vertical conductor connected with the anode extending through said upward extension of the anode chamber. 90

7. In an electrolytic cell, a U-shaped body forming the ends and bottom of the anode chamber metallic plates forming the sides of said cell and the cathode chambers, and walls presenting faces of inert material, 95 forming an upward extension of the anode chamber, the interior width of said extension being less than that of the anode chamber.

8. In an electrolytic cell, a U-shaped body 100 forming the ends and bottom of the anode chamber, metallic plates forming the sides of said cell, said plates having offset or outwardly extending central portions forming the cathode chambers, walls composed of non-conducting material forming an upward 105 extension of the anode chamber for increasing the hydrostatic pressure of the anolyte, ties or braces between the sides of said upward extension, and a vertical conductor connected with the anode and extending through the said upward extension of the anode chamber. 110

9. In an electrolytic cell, a U-shaped body forming the ends and bottom of the anode 115 chamber, metallic plates forming the sides of the said cell, said plates having offset or outwardly extending central portions forming the cathode chambers, and walls composed of non-conducting material forming an upward 120 extension of the anode chamber, the interior width of said extension being less than that of said anode chamber.

10. In an electrolytic cell, a U-shaped body forming the ends and bottom of the anode 125 chamber, metallic plates forming the sides of said cell, the said plates having offset or outwardly extending portions forming the cathode chambers, said offset portions having flat inner surfaces, and means bearing against 130

- said surfaces for holding the cathode and diaphragm in position transversely thereof.
11. In an electrolytic cell, a U-shaped body forming the ends and bottom of the anode chamber, metallic plates forming the sides of said cell and the cathode chambers, and walls presenting faces of inert material, forming an upward extension of the anode chamber, said plates overlapping the lower edges of the sides of said extension.
12. In an electrolytic cell, a U-shaped body forming the ends and bottom of the anode chamber, metallic plates forming the sides of said cell, said plates having offset or outwardly extending central portions forming the cathode chambers, and walls composed of non-conducting material forming an upward extension of the anode chamber, said plates overlapping the lower edges of the sides of said extension, exteriorly.
13. In an electrolytic cell, a U-shaped body forming the ends and bottom of the anode chamber, metallic plates forming the sides of said cell, said plates having offset or outwardly extending central portions forming the cathode chambers, and walls presenting faces of inert material forming an upward extension of the anode chamber, said plates impinging toward the lower edges of the walls of said extension, exteriorly, and a yielding packing between said last named parts.
14. In an electrolytic cell, an anode composed of plates of suitable material located parallel to each other, conductors located between said plates and to which said plates are attached, the outer faces of said plates being separated by a greater distance than the thickness of said conductors and plates.
15. In an electrolytic cell, a U-shaped body forming the ends and bottom of the anode chamber, metallic plates forming the sides of said cell, said plates having offset or outwardly extending central portions forming the cathode chambers, and walls presenting faces of inert material forming an upward extension of the anode chamber, an anode located in said anode chamber, and having its external surfaces separated by a distance less than the external width of said U-shaped body, the internal width of the sides of said extension being less than the distance between the external surfaces of the anode, so that said anode faces are beneath the sides of said extension.
16. In an electrolytic cell, a porous diaphragm, parts forming a substantially free outer cathode chamber, and a strip insulating liquid-proof material, situated vertically between the lower portion of said cathode chamber and said diaphragm, for separating any liquid draining into said cathode chamber, from said diaphragm.
17. In an electrolytic cell, a porous diaphragm, parts forming a substantially liquid free outer cathode chamber, a cathode of substantially the same shape and size as said diaphragm and a strip of insulating liquid-proof material situated vertically between the lower part of said diaphragm and said cathode chamber, for separating any liquid draining into the bottom of said cathode chamber, from said diaphragm.
18. In an electrolytic cell, a porous diaphragm, a cathode, a plate forming an outer cathode chamber, strips of inert material situated about the marginal portions of said diaphragm, so as to form a central opening smaller than said cathode chamber for preventing back percolation through the diaphragm.
19. In an electrolytic cell, a porous diaphragm, a cathode of substantially the same shape and size as said diaphragm, parts forming an outer cathode chamber, and strips of electrically insulating material situated about the marginal portions of said diaphragm so as to form a central opening smaller than said cathode chamber, for preventing back percolation through said diaphragm and for limiting the surface of the diaphragm that is active upon said cathode.
20. In an electrolytic cell, a porous diaphragm, a foraminous cathode of substantially the same shape and size as said diaphragm, a plate having a central offset portion forming an exterior cathode chamber, and insulating material situated about the marginal portions of said diaphragm and cathode so as to overlap the perforated marginal portions of said cathode and forming a central opening smaller than the area of said cathode chamber, said insulating material preventing back percolation through said diaphragm.

In witness whereof, I have signed my name in the presence of two witnesses, this 19th day of November, 1906.

GEORGE A. GABRIEL.

Corrections in Letters Patent No. 884,653.

It is hereby certified that in Letters Patent No. 884,653, granted April 14, 1908, upon the application of George A. Gabriel, of New York, N. Y., for an improvement in "Electrolytic Cells," errors appear in the printed specification requiring correction, as follows: In line 71, page 3, the word "Only" should be stricken out; in line 55, page 5, after the word "substantially," the word *liquid* should be inserted; and in line 56, page 5, after the word "strip," the word *of* should be inserted; and that the said Letters Patent should be read with these corrections therein that the same may conform to the record of the case in the Patent Office.

Signed and sealed this 19th day of May, A. D., 1908.

[SEAL.]

C. C. BILLINGS,

Acting Commissioner of Patents.
